UNITED STATES PATENT OFFICE

117,523

DESIGN FOR A BELT OR SIMILAR ARTICLE

Mortimer Marcus, New York, N. Y.

Application October 5, 1939, Serial No. 87,519

Term of patent 3½ years

To all whom it may concern:

Be it known that I, Mortimer Marcus, a citizen of the United States of America, residing in the city of New York, county of New York, and State of New York, have invented a new, original, and ornamental Design for a Belt or Similar Article, of which the following is a specification, reference being had to the accompanying drawing, forming part thereof,

Fig. 1 is a front perspective view of a belt or similar article showing my new design.

Fig. 2 is a rear view thereof.

I claim:

The ornamental design for a belt or similar article, substantially as shown.

MORTIMER MARCUS.
